FOLDING SHOE

Earl Arthur Westphal, Buffalo, N. Y., assignor to
 Bagpak, Inc., New York, N. Y., a corporation of
 Delaware

Application February 28, 1941, Serial No. 381,196

5 Claims. (Cl. 216—20)

This invention relates to new and useful improvements in tape applying apparatus and particularly seeks to provide a novel tape folding shoe adapted to be employed in connection with the tape handling and applying mechanisms of those machines which form the closures of filled bags formed from sheet material.

In machines of this nature, the open mouth of a filled bag is collapsed over the contents and secured in the collapsed position by closure securing elements or by lines of stitching. Where the contents of the bag are of such a nature that there is a tendency of such contents to sift through the apertures caused by the closure elements or stitches, it has been found desirable to seal the closure thus formed by applying an adhesively secured folded strip of tape to the end of the closure in such a manner that the folds of the tape extend over a portion of each side wall of the bag a distance sufficient to cover the closure securing elements. Many machines of this type commonly employ an ungummed tape supplied from a roll or reel mounted adjacent the tape applying station of the machine, and the tape during passage from the supply reel to the folding shoe is passed over adhesive supplying devices which adhesively coat one side of the tape. When the thus coated tape is passed through a folding shoe of the type heretofore employed, it frequently occurred that those portions of the adhesively coated side of the tape which were disposed in sliding contact with corresponding surface portions of the folding shoe were at least partially stripped of the adhesive. As the result of such contact, the adhesive which was thus disengaged from the tape tended to coagulate and ball up in the channels of the folding shoe and cause the tape to bind against the folding shoe to such an extent that the binding force was frequently sufficiently great to cause breaking of the tape during normal feeding operations thereof into engagement with the bag closure. This naturally necessitated corresponding shut-downs of the machine in connection with which the folding shoe was employed in order to free the shoe from the adhesive obstructions and rethread the tape through the shoe before the closing and sealing operations could be continued.

The above mentioned difficulties encountered in connection with prior types of folding shoes are overcome through the use of a folding shoe constructed in accordance with this invention.

It is therefore an object of this invention to provide for use in connection with bag closing

and sealing machines a novel type folding shoe which will maintain itself substantially free from loose particles of adhesive which may become disengaged from an adhesively coated tape passing therethrough.

A further object of this invention is to provide a device of the character stated which comprises an inverted, generally U-shaped channel whose walls progressively converge upon one another from a substantially flat condition at its leading end to a closely converged condition at its trailing end, and in which the outer edges of the channel are turned inwardly upon themselves to form guide flanges.

15 A further object of this invention is to provide a device of the character stated in which the guide flanges formed by the inturned edge portions of the channel are each provided with a plurality of spaced slots extending inwardly from the edge of such inturned portion whereby loose pieces of adhesive which may become disengaged from the tape during its passage through the folding shoe will be expelled through such slots and will not cause a binding of the tape against the adjacent portions of the folding shoe.

20 A further object of this invention is to provide a device of the character stated which is simple in design, rugged in construction and economical to manufacture.

25 With these and other objects in view, the nature of which will become more apparent, the invention will be more fully understood by reference to the drawings, the accompanying detailed description, and the appended claims.

In the drawings:

Fig. 1 is a fragmentary front elevation of the tape applying mechanism of a bag closing and sealing machine and showing a tape folding shoe constructed in accordance with this invention disposed in operative relation therein;

40 Fig. 2 is a longitudinal vertical section taken through the folding shoe and shows fragmentary portions of the mounting elements;

45 Fig. 3 is an enlarged bottom plan view thereof;

Fig. 4 is an enlarged transverse vertical section taken on line 4—4 of Fig. 2;

Fig. 5 is an enlarged transverse vertical section taken on line 5—5 of Fig. 2; and

50 Fig. 6 is a detail, enlarged longitudinal section taken along line 6—6 of Fig. 4, and shows particularly the manner in which free adhesive is expelled from the slots.

Referring to the drawings in detail, the invention as illustrated is embodied in the tape ap-

plying mechanisms of a bag closing and sealing machine and includes a main frame, generally indicated at A and supporting elements generally indicated at B mounted thereon, carrying the tape applying mechanisms. A tape 5 is withdrawn from a supply reel (not shown) and passed through engagement with suitable adhesive applying devices which may include an adhesive supply well 6, carried by the supports B. A dip roller 7 is arranged to dip into the adhesive within the well 6, while a cooperating spring mounted pressure roller 8 is adapted to press the tape 5 into contact with the upper surface of the dip roller and adhesive is transferred from the well to one face of the tape in the usual well known manner. From the adhesive applying rollers, the tape is carried over a suitable guide roller 9, rotatably mounted adjacent the supply well 6. The tape 5 is then conducted through a guide tube 10 of suitable rectangular cross section and which is supported upon a bracket 11 adjustably mounted upon the supports B to permit rotation of the bracket relative to the frame to facilitate proper alignment of the guide tube and the tape. From the tube 10, the tape is conducted around a freely rotatable guide roller 12, mounted upon supports generally indicated at 13, and is turned by this roller, with the adhesively coated side down, into a generally horizontal position overlying the path of the bag mouths in connection with the closing of which this apparatus is employed.

After the tape 5 has been directed into the generally horizontal position as described, it is then carried into operative engagement with a tape folding shoe generally indicated at 14. The folding shoe 14 comprises an inverted, generally U-shaped channel whose walls progressively converge upon one another from a substantially flat condition at the leading end as shown in Fig. 4 to the closely converged condition at the trailing end as shown in Fig. 5. The outer edges of the folding shoe 14 are preferably turned inwardly upon themselves to form guide flanges 15 within which the edges of the tape 5 are supported and guided. As indicated in Fig. 2, the tape 5 is conducted from the guide roller 12 into the leading end of the folding shoe 14 and at this point, is substantially flat in a transverse direction. The leading end of the tape former is provided with an upwardly flared lip portion 16 which facilitates passage of the tape into the folding shoe. The folding shoe as a whole is removably supported in operative position by mechanisms which form no part of the present invention, but which include the roller supporting elements 13, a lug 17 pivotally connected with the supports B, and a supporting stud 18. It should be mentioned, however, that the pivot element which supports the lugs 17 is removable to permit the leading end of the supporting elements 13 to be lowered and to then permit the folding shoe and its supporting members to be removed bodily from the machine with which it is associated. The folding shoe 14 is supported in a downwardly inclined position in which the trailing end thereof is yieldably urged towards contact with the top of a bag mouth (not shown) to which the tape is being applied.

The supporting elements B also carry a pair of power driven cooperating tape feed rollers, generally indicated at 19, which effect the feeding of the tape from the supply reel over the various adhesive applying and guide rollers and through the folding shoe, and actively press the folded

tape into contact with the opposite sides of a bag mouth associated therewith.

As the tape 5 is pulled through the folding shoe by the action of the feed rollers 19, it frequently occurs that small portions of the adhesive which has been applied to the under side of the tape will come into sliding contact with the opposed surface portions of the inturned edges 15 of the folding shoe and be rubbed off or disengaged from the surface of the tape as a result of such contact. Means must be provided to facilitate and effect the removal of any such loose adhesive material in order to prevent binding of the tape relative to the corresponding portions of the folding shoe, and to prevent breaking of the tape as the result of such binding. Therefore, the bottom longitudinal edge portions of the channels 15 are each provided with a plurality of spaced slots 20 which are preferably located along the leading half of the folding shoe but which may also be located along the trailing half of the folding shoe should it become desirable. Thus, as the tape 5 is drawn into the leading portion of the folding shoe, the edge portions 25 will be in sliding contact with the corresponding portions of the inturned channels 15 which is likely to cause disengagement of some of the adhesive from the tape. In Fig. 6 of the drawings, there is illustrated the manner in which adhesive, 30 which has been thus disengaged from the tape, is carried by movement of the tape along the bottom of the inturned channels 15 and upon reaching the slot 20, will be ejected or will drop from the folding shoe. It is obvious that when 35 loose adhesive is expelled from the folding shoe in this manner, it would be quite difficult, if not impossible, for loose adhesive to build up in the inturned channels 15 to such a degree that it will effect binding of the tape against the corresponding portions of the folding shoe.

Thus, the herein described invention discloses a novel folding shoe for use in conjunction with the tape applying mechanisms of a bag mouth closing and sealing machine which is so constructed that clogging of the tape receiving channels thereof will be eliminated as will breakage of tape passing therethrough and which is simple in design, rugged in construction, and economical to manufacture.

50 It is, of course, to be understood that certain details of arrangement and proportions of parts may be variously modified without exceeding the scope of the appended claims.

I claim:

55 1. A folding shoe for use in conjunction with tape applying mechanisms and comprising a generally U-shaped channel provided with spaced guide flanges adapted to support the edge portions of an adhesive tape strip as said strip is being moved therewith, said guide flanges each being slotted to permit the expulsion therefrom of any adhesive particles that become disengaged from said strip whereby binding of the strip against the adjacent portions of said guide flanges will be prevented.

60 2. A folding shoe for use in conjunction with tape applying mechanisms and comprising a generally U-shaped channel provided with inturned guide flanges adapted to support the edge portions of an adhesive tape strip as said strip is moved therewith, the longitudinal edge portions of said channel being slotted to permit the expulsion from said guide flanges of any adhesive particles that become disengaged from said strip whereby binding of the strip against the adjacent

portions of said guide flanges will be prevented.

3. A folding shoe for use in conjunction with tape applying mechanisms and comprising an inverted generally U-shaped channel whose walls progressively converge upon one another from a substantially flat condition at one end to a closely converged condition at the other end, and in-turned guide flanges formed along the outer edges of said channel and being adapted to support the edge portions of an adhesive tape strip as said strip is moved therealong, said guide flanges being slotted to permit the expulsion therefrom of any adhesive particles that become disengaged from said strip whereby binding of the strip against the adjacent portions of said guide flanges will be prevented.

4. A folding shoe for use in conjunction with tape applying mechanisms and comprising an inverted generally U-shaped channel whose walls progressively converge upon one another from a substantially flat condition at one end to a closely converged condition at the other end, and in-turned guide flanges formed along the outer edges of said channel and being adapted to support the edge portions of an adhesive tape strip

as said strip is moved therealong, each of said guide flanges being provided with a plurality of slots to permit the expulsion of any adhesive particles that become disengaged from said strip whereby binding of the strip against the adjacent portions of said guide flanges will be prevented.

5. A folding shoe for use in conjunction with tape applying mechanisms and comprising an inverted generally U-shaped channel whose walls progressively converge upon one another from a substantially flat condition at one end to a closely converged condition at the other end, and in-turned guide flanges formed along the outer edges of said channel and being adapted to support the edge portions of an adhesive tape strip as said strip is moved therealong, each of said guide flanges being provided with a plurality of slots extending across the full width thereof to permit the expulsion therefrom of any adhesive particles that become disengaged from said strip whereby binding of the strip against the adjacent portions of said guide flanges will be prevented.

25

EARL ARTHUR WESTPHAL.
